UNITED STATES PATENT OFFICE

2,572,953

FLOATING PRESS HEAD

Thomas A. Saari, Chicago, Ill., assignor, by mesne assignments, to Baldwin-Lima-Hamilton Corporation, a corporation of Pennsylvania

Application August 19, 1948, Serial No. 45,113

8 Claims. (Cl. 18—16)

1

This invention relates to presses and in particular to mechanism that at least in part is hydraulic in nature and that may be used with a crank-operated press to provide a dwell or interval of time during the stroke of the press during which time a substantially constant pressure is exerted on the material being pressed.

Crank-operated presses have been used for many operations including the compacting of plastic powders in the production of preforms for use in compression molding. While some plastics in powder form may be satisfactorily compacted in a crank-operated press, other plastic powders require that the pressure be maintained for an appreciable length of time. An ordinary crank-operated press, since the travel of the ram is determined by the crank throw, can not apply a steady pressure without actually stopping the crank with the ram in contact with the material. This type of operation, however, is impractical, if not impossible, because a heavy flywheel is employed to store energy which is delivered to the ram during the compacting stroke. As long as a flywheel is employed in this manner the crank can not be readily started and stopped during each revolution.

The principal object of this invention is to provide a hydraulic mechanism that acts preferably between the crank-operated head of a press and the ram which applies the pressure to the material being compacted and which hydraulic mechanism serves to maintain a constant pressure on the material being compacted during an appreciable portion of the stroke of the press.

Another object of the invention is to provide a relief mechanism in the moving head of a crank-operated press which relief mechanism permits relative movement between the ram of the press and the moving head when the force exerted by the ram exceeds a predetermined limit.

A still further object of the invention is to provide in the moving head of a crank-operated press a plurality of axially aligned cylinders, at least some of which are equipped with pistons and filled with hydraulic fluid.

Another object of the invention is to provide a hydraulic cylinder in the moving head of a crank-operated press and arranging that cylinder so that it acts as a pump and by pumping fluid against a predetermined back pressure determines the maximum force with which the moving head acts against the ram.

A still further object of the invention is to provide a hydraulic cylinder in the moving head of a crank-operated press, which cylinder is con-

2

nected to a source of hydraulic fluid that is maintained under a predetermined pressure so that the maximum force with which the head acts against the ram is limited and which by providing relative movement between the ram and the moving head permits an extension of the time during which the ram acts against the material being pressed.

More specific objects and advantages are apparent from the following description in which reference is made to the accompanying drawings illustrating preferred embodiments of the invention.

In the drawings:

Figure I is a front elevation of a crank-operated press the head of which is provided with a hydraulic cylinder according to the invention.

Figure II is an enlarged vertical section of the hydraulic cylinder assembly that is mounted on the moving head of the press shown in Figure I.

Figure III is a vertical section of an indicator and limit switch operating mechanism that is employed to supervise the operation of the hydraulic cylinder.

Figure IV is a modification of the hydraulic cylinder in which it acts as a self-contained pump to limit the maximum force that is exerted by the ram.

Figure V is a vertical section of a modified form of structure embodying the invention.

Figure VI is a diagrammatic illustration of the hydraulic connections to the mechanism illustrated in Figure V.

Figure VII is a vertical section of still another embodiment of the invention.

Figure VIII is a diagrammatic sketch showing the hydraulic connections for the hydraulic cylinder shown in Figure VII.

These specific figures and the accompanying description are intended merely to illustrate the invention but not to impose limitations on the claims.

Referring now to the accompanying drawings, a crank-operated press in which the invention may be advantageously employed includes a base 1 within which is mounted crank mechanism for reciprocating tie rods 2 that support a head mechanism 3. The crank mechanism is conventional and is driven by a motor or other suitable source of power that is not shown.

The crank mechanism within the base 1 is also arranged to reciprocate a lower punch that serves as the bottom of the die cavity of the press and that also serves to eject the compacted article at the finish of each stroke. The height and travel

of the lower punch is controlled by a hand wheel 4 that is carried on a shaft protruding from the front of the base 1.

The head mechanism 3 includes a cylindrical portion 5 the upper part of which forms the body of a hydraulic cylinder. Above the cylindrical portion 5 is a necked-down section 6 and a second cylindrical portion 7 which, in this embodiment of the invention, is the housing of an air cylinder.

Referring now to Figure II, the head mechanism 3 includes a platen 8 to which a ram may be attached. The platen 8 is supported against upward movement by a heavy externally-threaded sleeve 9 the threaded portion of which engages an internally-threaded sleeve 10 the upper end of which is press-fitted into a recess in a piston 11, which in turn is slidably mounted within the upper cylindrical portion of the casing 5. To prevent rotation, the platen 8, which is circular in plan, has a keyway 12 that cooperates with a key 13 secured in an annular insert 14 fitted into the bottom open end of the head portion 5. Likewise, the piston 11 and the press-fitted internally-threaded sleeve 10 are prevented from rotating by the cooperation of a spring-pressed key 15 and a vertical slot 16 cut in the side of the internally-threaded sleeve 10.

A bolt 17 the lower end of which is secured to the platen 8 extends axially through the heavy sleeve 9 with its head 18 contained within a counterbore 19 at the upper end of the heavy externally-threaded sleeve 9. The bolt 17 serves to support the platen against the lower end of the heavy sleeve 9.

A ring 20 slidably mounted on the heavy sleeve 9 is keyed to the sleeve and is held in position between the upper surface of the annular insert 14 and the lower surface of the internally-threaded sleeve 10. Rotation of the ring 20 serves to screw the heavy sleeve 9 into or out of the internally-threaded sleeve 10 to adjust the height of the platen 8 with respect to the head mechanism 3.

The ring 20 is provided with gear teeth 21 that mesh with a pinion 22 that is carried on a vertical axle 23 the lower end of which is journaled in a hole drilled in the upper surface of the annular insert 14 and the upper end of which is journaled in a hole drilled in an inwardly-directed flange 24 of the cylindrical head portion 5. The hub of the pinion 22 is formed with bevel gear teeth 25 that mesh with a bevel gear 26 carried on the inner end of a shaft 27 the other end of which is provided with a hand wheel 28. The shaft 27 is carried in a long cylindrical bearing 29 that is set into the side of the circular head portion or casting 5. Rotation of the hand wheel 28 acting through the bevel gear 26, pinion 22, and the ring 20 serves to adjust the height of the platen 8. The hand wheel 28 is fixedly held in adjusted position by a lock controlled by a laterally extending handle 30 located adjacent the hand wheel 28.

The piston 11 is slidably contained within a cylindrical bore 31 of the head portion 5 and is provided with suitable packings 32 and a cover plate 33 for holding the packings 32 in place. The space between the upper plate 33 of the piston 11 and a cover 34 closing the top of the bore 31 is filled with hydraulic fluid under pressure for urging the piston 11 down against the inwardly-directed flange 24. Any fluid that leaks past the packing members 32 is collected in an annular trough 35 and drained from the trough through a downwardly-inclined hole 36 leading to the outside of the head portion 5.

The necked-down portion 6 is provided with a small diameter hydraulic piston 37 the upper end of which is attached to a large diameter piston 38 slidably mounted within the upper cylindrical portion 7 of the head mechanism 3. The large diameter piston 38 includes a bottom plate 39 into which a tenon of the small diameter piston 37 is secured, a sealing diaphragm 40 and an upper plate 41 that holds the diaphragm 40 in position against the lower plate 39. Air under pressure is admitted through a pipe 42 secured into a cover 43 that closes the upper end of the cylindrical section or air cylinder 7. The pressure of the air admitted through the pipe 42 acting against the upper surface of the air piston 38 drives the small diameter hydraulic piston 37 downwardly through the necked-down portion 6 so that the small diameter hydraulic piston 37 exerts pressure within the chamber over the piston 11. Leakage of fluid past the small diameter hydraulic piston 37 is prevented by sealing rings 44 installed in the upper end of the necked-down portion 6. In this assembly, as the head of the press moves down and a ram connected to the platen 8 engages the material to be compacted, the force acting against the platen 8 increases until finally that force exceeds the force exerted by the hydraulic fluid against the piston 11 so that the piston 11 lifts with respect to the head mechanism 3. As it rises it forces the small diameter hydraulic piston 37 upwardly through the necked-down portion 6, thereby either compressing the air within the air cylinder or driving the air out of the cylinder to an accumulator or through a pressure relief valve. As the head of the press reaches the bottom of its stroke and starts upward the compressed air within the air cylinder 7 still urges the piston down thereby driving the small diameter hydraulic piston 37 and the piston 11 downward to maintain the pressure applied to the ram even though the head of the press is moving upwardly. The pressure against the ram is maintained until the bottom of the piston 11 again comes to rest on the inwardly-directed flange 24. The pressure exerted by the ram against the work may be easily controlled by adjusting the air pressure within the air cylinder. The air pressure need not be extremely high because a great multiplication of force results from the differences in piston areas of the hydraulic and air pistons.

As a check on the operation of the air piston 38 and incidentally as a measure of the quantity of hydraulic fluid contained in the chamber over the piston 11, the air piston 38 is provided with an indicator rod 45 that extends up through a packing gland 46 and which at its upper end carries an indicator arm 47 (Figure III). The indicator arm 47 projects laterally from a guard 48 that is erected from the air cylinder cover 43. A pair of limit switches 49 and 50 may be included in the guard 48 and connected to auxiliary equipment suitable for supervising the operation of the press.

In normal operation of the mechanism, the indicator arm 47 never strikes or actuates the lower limit switch 49 because the downward movement of the air piston 38 and small diameter hydraulic piston 37 is checked when the large hydraulic piston 11 strikes the inwardly-directed flange 24. The normal quantity of hydraulic fluid contained within the chamber holds the air piston 38 above the bottom possible limit of its travel so that pressure is maintained on the hydraulic fluid at all times. If hydraulic

fluid leaks from the chamber the air piston 38 settles and eventually the limit switch 49 is actuated to give an indication that the hydraulic fluid must be replenished.

In normal operation of the device the air piston 38 is never driven to its upper limit of travel but such movement may result if, for some reason such as failure to reject a previously compacted article, an excessive amount of material is being compacted under the ram. In this event the pistons are forced to their upper limits of travel and the indicator arm 47 is driven against the upper limit switch 50 which switch may be connected to activate a safety device such as a throw-out clutch effective to immediately stop the operation of the press.

This structure is relatively simple to adjust in that the maximum pressure is controlled entirely by the air pressure maintained within the air cylinder 7 and that there is only one set of cylinders to be maintained in operative condition so there is not question of balance between various elements. Furthermore, the parts are all simple and easy to construct.

Figure IV shows a modification of the upper portion of the head mechanism in which a hydraulic cylinder 51 is substituted for the air cylinder 7. In this example a small diameter hydraulic piston 52 which corresponds to the small diameter hydraulic piston 37 of Figure II carries a larger piston 53 on its upper end. The piston 53 is urged downwardly within the cylinder 51 by a heavy conical spring 54 that is held compressed between the upper surface of the piston 53 and a cap 55 of the cylinder 51. When the piston 53 moves up as a result of pressure applied to the ram by downward movement of the head mechanism the tension of the spring 54 is overcome and hydraulic fluid within the cylinder 51 is forced out through a spring loaded pressure relief valve 56 which valve discharges through a pipe 57 into a reservoir 58. The pressure maintained by the relief valve 56 is sufficient to supply the required force at the ram.

When the press head mechanism moves upwardly after a compression stroke and the pressure on the ram is released the spring 54 drives the pistons down and the hydraulic fluid is drawn from the reservoir 58 through a check valve 59 into the hydraulic cylinder 51.

This arrangement is self-contained in that it requires no external source of air or fluid under pressure but it has the disadvantage that it does not maintain pressure on the material being compacted during the initial upward movement of the head mechanism in a manner corresponding to the pressure exerted as a result of the expansion of the air within the air cylinder 7. This follows because the pressure within the hydraulic cylinder 51 must be reduced below atmospheric pressure before the check valve 59 can open to admit hydraulic fluid from the reservoir 58 and allow the piston 53 to descend.

Another example is illustrated in Figures V and VI. In this example a head mechanism 60 that is carried on tie rods 61 includes a cylindrical casing 62 forming a cylinder in which a hydraulic piston 63 is slidably mounted. The piston 63 is provided with packing means 64 that are held in place by an upper piston plate 65. The piston 63 is urged downwardly within the cylinder 62 by a heavy helical spring 66 that is held compressed between the upper piston plate 65 and a cap 67 closing the upper end of the cylinder. The downward travel of the piston 63

is limited by an annular inwardly-directed flange 68 that engages the outer portion of the under surface of the piston 63. An annular groove 69 cut at the outer edge of the annular flange 68 collects any hydraulic fluid that may leak past the packing means 64 and this leakage fluid is drained through a duct 70 leading to the outside of the cylinder 62.

The piston 63 has an integral downwardly-directed internally-threaded sleeve portion 71 that is guided through the flange 68 and into which is screwed an externally-threaded heavy sleeve 72. A bolt or stud 73 that is fitted with a nut 74 set in a counterbore at the upper end of the heavy externally-threaded sleeve 72 is threaded into a platen 75 and serves to support the platen against the lower end of the heavy sleeve 72. The platen 75 is guided in an annular insert 76 set in the lower end of the cylinder 62 and is prevented from rotating therein by a key 77 that engages a slot 78 milled in the periphery of the platen 75. The piston 63 is also prevented from rotating within the cylinder 62 by a vertical pin 79 that fits into holes drilled in the upper surface of the inwardly-directed flange 68 and the lower surface of the piston 63.

Adjustment of the height of the platen 75 is accomplished by rotating the heavy sleeve 72 with respect to the piston 63 and for this purpose the sleeve 72 is provided with a ring of gear teeth 80 that mesh with an elongated pinion 81. The pinion 81 at one end is formed with bevel gear teeth 82 that are engaged by a bevel gear 83 mounted on the inner end of a shaft 84 the outer end of which carries a hand wheel 85. A lock 86 serves to hold the hand wheel in adjusted position and thus maintain the lower position of the platen 75 with respect to the head mechanism 60.

As the head mechanism moves downwardly to compact material within a die and a ram attached to the platen 75 applies a preselected maximum force to the material, the piston 63 moves upwardly within the cylinder 62 thereby compressing the spring 66 and at the same time forcing a small hydraulic piston 87 upwardly through a necked-down portion 88 of the head mechanism 60. The small diameter hydraulic piston 87 carries a large diameter piston 89 on its upper end and the piston 89 is slidably mounted within an upper cylinder 90.

Referring to Figure VI, the upper cylinder 90 is connected through a flexible hydraulic lead 91 and a small accumulator 92 to a source of pressure that serves to maintain a constant pressure within the cylinder 90 regardless of changes in volume. A pressure gauge 93 may be employed to indicate the pressure within the cylinder 90.

In this example, as in the preceding examples, a portion of the head mechanism is yieldably held in the head mechanism so that the force applying member or ram may remain stationary during an appreciable portion of the stroke of a crank-operated press. In each of these examples a plurality of hydraulic cylinders or hydraulic and pneumatic cylinders are arranged in axial alignment in the head mechanism of the press. This arrangement is extremely simple to manufacture and very serviceable in use.

Still another example of a crank-operated press head mechanism embodying the invention is illustrated in Figures VII and VIII.

In this example a head mechanism 94 is supported on crank-operated tie rods 95 arranged to reciprocate the head in a vertical direction. The head mechanism 94 includes a hydraulic

cylinder 96 containing a piston 97 which, when hydraulic fluid is admitted under pressure to the space above the piston 97, drives the piston 97 downwardly within the cylinder 96 until its bottom peripheral portion 98 engages an inwardly-directed flange 99 of the cylinder 96. The piston 97 is provided with packings 100 that, being held in place by a piston top plate 101, serve to prevent the leakage of hydraulic fluid past the piston. Any seepage of hydraulic fluid past the piston is collected in an annular trough 102 and drained through a drain 103.

The underside of the piston 97 is provided with a downwardly-directed internally-threaded sleeve 104 which is guided in a bushing 105 set in the inwardly-directed flange 99 and which, to prevent rotation of the piston, is provided with a keyway 106 that cooperates with a spring-pressed key 107.

A heavy externally-threaded sleeve 108 that is threaded into the internally-threaded sleeve 104 supports a platen 109 against upward movement. The platen 109 is held against rotation by a key 110 set into the bottom surface of an annular insert 111. The annular insert 111 surrounds the heavy sleeve 108 and supports an annular gear 112 that is slidably keyed to the heavy sleeve 108. The platen 109 is held up against the heavy sleeve 108 by a stem 113 that extends upwardly through the heavy sleeve 108 and at its upper end is fitted with a nut 114.

This arrangement of elements permits the height of the platen 109 to be adjusted with respect to the hydraulic cylinder 96 by rotation of the heavy externally-threaded sleeve 108 within the piston sleeve 104. This rotation of the sleeve is accomplished by a hand wheel 115 carried on the end of a shaft 116 the inner end of which carries a bevel gear 117 meshing with beveled gear teeth 118 formed on the upper end of a pinion hub 119. The pinion hub 119 has a pinion 120 meshing with the annular gear 112 and is supported on a vertical shaft 121 the upper end of which is journaled in the inwardly-directed flange 99 and the lower end of which is journaled in the annular insert 111.

The piston 97 is yieldably held in its lowermost position within the head mechanism 94 by hydraulic fluid held in the space above the piston. When the load applied to the platen 109 during the compacting of material within the press exceeds the pressure of the hydraulic fluid some of the fluid is forced from the hydraulic cylinder thus permitting the platen 109 and piston 97 to move upwardly with respect to the head mechanism 94. During this upward movement a steady pressure is maintained on the material being compacted even though the head mechanism 94 is still moving downwardly. It is to be remembered that the head mechanism 94 is actuated by a crank mechanism and, therefore, executes a positively determined movement and that the pressure applied to the material being compacted except for the influence of the hydraulic cylinder is determined entirely by the quantity of material within the die of the press. The hydraulic cylinder modifies this relationship by setting a maximum pressure that can be applied and permitting relative motion between the platen and the head mechanism as soon as the predetermined pressure is reached.

Hydraulic fluid flows to and from the chamber within the cylinder 96 by way of a conduit 122, a slide connector 123, and a second conduit 124 leading to a source of hydraulic fluid. The sliding connector 123 comprises a sleeve 125 that

is connected to the head mechanism 94 so as to reciprocate therewith and a hollow plunger rod 126 that is mounted from a shelf 127 of the base 128 of the press. The interior of the plunger rod 126 communicates directly with the second conduit 124. Suitable packings 129 and 130 at the ends of the sleeve 125 prevent the escape of hydraulic fluid along the sides of the plunger rod 126 and at the same time form an annular chamber within the sleeve and surrounding the plunger rod 126. A hole 131 drilled in the wall of the plunger rod 126 provides fluid communication between the annular chamber in the sleeve 125 and the interior of the plunger rod 126.

The mounting for the slide connector 123 includes a pair of arms 132 projecting laterally from the head mechanism 94 and embracing an arm 133 that projects laterally from the sleeve 125. A bolt 134 threaded through the ends of the arms 132 and the arm 133 holds the parts in assembled relationship while permitting a small amount of play so that the sleeve 125 may accurately follow the plunger rod 126 without excessive friction or binding.

Since the plunger rod 126 projects from each end of the sleeve 125 the hydraulic pressures are balanced and there is no tendency for the hydraulic pressure to generate a force in the slide connector tending to raise or lower the head mechanism 94.

Referring now to Figure VIII, the conduit 124 is connected through a pressure regulator 135 to a conduit 136 leading to a source of hydraulic fluid that is maintained under high pressure. The conduit 124 is connected through a branch conduit 137 to a pressure relief valve 138 the discharge of which is led through a conduit 139 and back to the pump that maintains pressure on the conduit 136. In this arrangement the pressure relief valve is set to discharge fluid when the pressure in the cylinder 96 and the conduit 124 or 137 exceeds by a small margin the pressure for which the regulator 135 is set. With this adjustment the piston 97 is urged downwardly within the cylinder 96 until it reaches its lower limit of travel and the pressure within the cylinder and within the conduits 122 and 124 is equal to the pressure at which the pressure regulator 135 is set.

During a pressing cycle, when the force exerted by the platen 109 exceeds the force exerted by the hydraulic fluid against the upper surface of the piston 97, the piston 97 rises within the cylinder 96 and fluid is discharged through the relief valve 138 as long as the hydraulic pressure within the system exceeds the pressure at which the relief valve is set. After the crank mechanism of the press passes its dead center position the flow of fluid through the relief valve stops and the piston is urged downwardly within the cylinder 96 with a force proportional to the pressure supplied by the pressure regulator 135. As the head mechanism 94 moves upwardly to relieve the force applied to the material being compacted, fluid flows from the source of pressure through the conduit 136 and the pressure regulator 135 to maintain the pressure of the platen 109 on the material until the piston 97 reaches its lower limit of travel with respect to the head mechanism 94. As the head mechanism 94 continues to rise, there is no further transfer of hydraulic fluid and the hydraulic system maintains itself in readiness for the next cycle of operation.

The improved press head mechanism including a hydraulic cylinder and a pressure controlling mechanism offers many advantages over a conventional crank-operated press. Among these advantages is the possibility of maintaining pressure on a material being compacted throughout an appreciable portion of the cycle of operation so that a wider variety of materials, particularly those requiring a sustained pressure, may be handled by the press. Another important advantage is the freedom from the possibility of jamming the press by the accidental overfilling of the die cavity because in such an event the piston and platen merely travel an additional distance without exerting excessive pressure against the parts of the press. In the event that the yieldable feature of the invention is not required the overload feature may be accomplished with very little extra expense by employing a self-contained hydraulic mechanism such as is illustrated in Figure IV and in such a mechanism setting the pressure relief valve 56 at a pressure slightly greater than that required for the normal operation of the press.

Various modifications of the structure may be made without departing from the spirit and scope of the invention.

Having described the invention, I claim:

1. The combination in a crank operated press of the type having a mold cavity and a head mechanism that is reciprocated with a compression and a return stroke of fixed length in a direction axially of said cavity, comprising, a ram for compressing material in said cavity, a cylinder in the head mechanism, a ram supporting member that is axially slidably mounted in said cylinder, means whereby the head and supporting member simultaneously move toward the cavity at the same speed and in a predetermined axially fixed relation to each other until the ram starts to compress material in the cavity, means movable with the head mechanism for varying said fixed axial relation of the ram so that different thicknesses of material may be compressed in the cavity, and means for maintaining a substantially constant hydraulic fluid pressure in said cylinder and against said ram supporting member so that on the compression stroke it can yield after engaging material in the cavity and on the return stroke its predetermined fixed relation can be re-established preparatory for the next compression stroke.

2. The combination set forth in claim 1 further characterized in that the ram supporting member includes a piston in the cylinder upon which the hydraulic fluid acts, and means for diverting from said cylinder any leakage of hydraulic fluid past said piston whereby material in the cavity is kept free of contamination from leakage fluid.

3. The combination set forth in claim 1 further characterized in that the ram supporting means includes a piston in the cylinder, and the means for effecting simultaneous movement of the head and ram supporting member includes opposed surfaces on said cylinder and piston engaging each other during the compression stroke until separated upon compression of the cavity material.

4. The combination set forth in claim 1 further characterized in that the ram supporting means includes a piston in the cylinder, and the means for effecting simultaneous movement of the head and ram supporting member includes opposed radially extending surfaces on said cylinder and

piston for engagement with each other during the compression stroke until separated upon compression of the cavity material, and means for diverting from said cylinder any leakage of hydraulic fluid past said piston including an annular groove formed at the end of the cylinder toward the mold cavity and surrounding said radial surfaces.

5. The combination set forth in claim 1 further characterized in that the ram supporting means includes a piston, and the means for effecting simultaneous movement of the head and ram supporting member includes opposed annular surfaces on said cylinder and piston for engagement with each other during the compression stroke until separated upon compression of the cavity material, an annular groove formed at the end of the cylinder toward the mold cavity, said groove surrounding said annular surfaces and extending below the level thereof, and an annular portion on said piston projecting into said annular groove thereby providing a surface extending upwardly to the radial surface of the piston.

6. The combination set forth in claim 1 further characterized in that the ram supporting member includes an axially extending rotatable sleeve upon which the ram is mounted, and the means for varying the fixed axial relation of the ram relative to the head includes a threaded connection between said sleeve and the remainder of the ram supporting member and gearing connected to said sleeve below said threaded connection for rotating the sleeve and thereby effecting axial adjustment of the ram.

7. The combination set forth in claim 1 further characterized in that the ram supporting member includes an axially extending rotatable sleeve, and the means for varying the fixed axial relation of the ram relative to the head includes a threaded connection between said sleeve and the remainder of the ram supporting member, gearing connected to said sleeve below said threaded connection for rotating the sleeve and thereby effecting axial adjustment of the ram, said gearing including a gear encircling said sleeve and being relatively axially slidable but non-rotatable with respect thereto.

8. The combination set forth in claim 1 further characterized in that the ram supporting member includes an axially extending rotatable sleeve, and the means for varying the fixed axial relation of the ram relative to the head includes a threaded connection between said sleeve and the remainder of the ram supporting member, a gear encircling the sleeve below said threaded connection for rotating the sleeve and thereby effecting axial adjustment of the ram, and gearing for operating said encircling gear having a shaft extending laterally from within the head mechanism to the outside thereof.
